ROLLED PASSIVE REFLECTIVE ANTENNA TENDING TO UNROLL UNDER BIAS OF ENTRAPPED AIR

Trevor Clark, Annapolis, Md., assignor to Westinghouse Electric Corporation, Pittsburgh, Pa., a corporation of Pennsylvania

Filed Oct. 26, 1962, Ser. No. 233,293

2 Claims. (Cl. 343—915)

The present invention relates to radio antennas and more particularly to a passive reflective foldable antenna that may be unfolded to be erected and orbited in space.

Reflective antennas orbiting in space are useful for extending the transmission of short wavelength radiations and microwave radio communications to points all around the earth as is well known to those skilled in the art. The so-called "Echo Satellite" is a balloon with a reflective surface for electromagnetic radiations that has been orbited in spaced and inflated. However, for various reasons, the balloon gradually is losing its spherical shape and has become wrinkled so that it is less efficient and effective as a reflector for electromagnetic radiations. Another form of passive reflector for electromagnetic radiations was attempted to be obtained by ejecting into space a cloud of metallic filaments called needles which were intended to function as reflective dipoles for a band of frequencies of electromagnetic radiations. This form of antenna has thus far failed to be achieved in that the needles apparently dispersed and were lost in space.

It is a principal object of the present invention to provide an improved form of foldable wide band dipole passive reflective antenna that may be easily unfolded to be erected after being orbited in space and that will retain its reflective effectiveness as a communications satellite indefinitely.

Another object of the invention is to provide a simplified form of omnidirectional and broad band dipole passive reflective antenna that may be easily erected and randomly oriented in space and which will function effectively without critically as to its position and attitude relative to the radiation to be reflected.

A still further object of the invention is to provide an improved form of orbiting passive reflective antenna that is substantially immune to damage from micrometeorites and particles in space and that is not deleteriously affected by varying exposure to heat and light rays from the sun and to other objects in space.

According to the invention, a relatively large thin panel of electrically insulative and foldable sheet material is arranged to be folded in the nose cone of a rocket from which it may be ejected to orbit in space and unfolded. The foldable panel may be provided with suitable means to assure the unfolding of the panel in space when it is ejected. For example, longitudinal hollow ribs may be provided on the panel to contain atmosphere, a gas under pressure, or a coiled or rolled spring to unfold the panel when ejected into space. At least one planar surface of the panel is provided with a large plurality of randomly oriented metallic elements secured thereto such as, for example, filaments of aluminum or similar high conductivity metal having a length equal to one half the wavelength of the electromagnetic radiation to be reflected. If a specified band of frequencies of electromagnetic radiations is to be reflected, then the randomly oriented metallic filaments may be of various different individual lengths varying from a minimum length to a maximum length corresponding to the minimum and maximum wavelengths of energy to be reflected. Thus, such random oriented filaments may function as an omnidirectional broad band reflective antenna with substantially

2

no particular polarization relative to received energy to be reflected. It should be borne in mind that the thin sheet of insulating material forming the panel for supporting and fixing the metallic filaments in random orientation to each other in accordance with the invention, is itself essentially transparent to the electromagnetic radiations and hence there is no need to orient or stabilize the position of the reflector panel in space since the dipoles will re-radiate in all directions almost as does the re-radiating sphere of the so-called "Echo Balloon" type.

Further objects, features and the attending advantages of the invention will be apparent with reference to the following specification and drawing, in which:

FIGURE 1 is a fragmentary perspective elevational view of the passive reflective antenna of the invention in the unfolded state;

FIG. 2 is an enlarged fragmentary detail perspective of a portion of the panel of FIGURE 1 showing one arrangement of randomly oriented metallic reflecting elements on its planar surface;

FIG. 3 is an elevational view of the reflective panel of FIGURE 1 as it may be partially rolled for stowage in a missile nose cone or the like;

FIG. 4 is a detailed fragmentary perspective view partly broken away to show a modified form of panel unfolding means;

FIG. 5 is an enlarged fragmentary sectional view of a modified form of reflective panel;

FIG. 6 is an enlarged fragmentary sectional view of yet another modified form of reflective panel of the invention.

Referring now to FIGS. 1-3 of the drawing, one form of the invention will now be described in some detail. A thin sheet of plastic electrically insulating material 10 is provided in any desired shape, configuration or area as a support sheet for a plurality of electrically conductive reflective members such as metallic filaments of aluminum or the like. Various ones of the metallic filaments are shown at 11 by FIGURE 2 of the drawings. The metallic filaments are cut to a length equivalent to one half wavelength of the electromagnetic energy to be reflected so that each filament effectively functions as a reflective dipole. If the electromagnetic energy to be reflected is a band of wavelengths having lower and upper limits, then individual ones of the metallic filaments 11 would be cut to individually different lengths varying from the minimum length corresponding to one half wavelength of the minimum wavelength of energy to be reflected to a maximum length corresponding to one half wavelength of the maximum wavelength of electromagnetic energy to be reflected.

As shown by the enlarged view of FIGURE 2 of the drawing, each of the metallic filaments 11 is randomly positioned on the electrically insulative supporting sheet or panel 10. The random positioning may be in reference both to the position of orientation and the occurrence of varying lengths of the individual filaments which may also be randomly occurring in various positions on the supporting panel 10. For example, each of various lengths of the metallic filaments 11 may be all secured in the same plane as the planar surface of the supporting sheet 10. On the other hand, each of the metallic filaments 11 may be secured to the planar surface of the supporting sheet 10 at varying angles to the plane of the supporting sheet and to each other. It should be apparent that, regardless of the angular position or orientation of individual ones of the metallic filaments 11 on the planar surface of the supporting sheet 10, there will be no particular polarization emphasis for the reflective nature of the antenna comprising the plurality of random oriented filaments.

nents. This will be understood when it is borne in mind that the electrically insulative sheet 10 of thin material is effectively transparent to the electromagnetic radiations to be re-radiated by the various randomly disposed metallic dipole elements 11.

Each of the metallic elements 11 may be secured in random position relative to each other on the electrically insulative supporting sheet 10 by any suitable means. For example, a layer of adhesive material 12 may be secured to a surface of the supporting sheet 10 and the metallic needle elements 11 may be simply sown onto the adhesive layer much in the manner of sowing grain. If a particular sensitivity toward a desired range of frequencies for the electromagnetic radiations to be re-radiated is desired, it would be preferable to remove any of the electrical elements 11 that are physically contacting other metallic elements in a manner to alter the effective dipole length of such metallic elements. However, depending upon the efficiency desired, it is not in all cases necessary to preserve a complete electrical independence for each of the metallic elements 11. Also, although the metallic elements 11 are shown to be secured to one side only of the supporting sheet 10, it is within the purview of the invention to also secure additional reflective elements 11 to the other side of the supporting planar sheet 10.

The adhesive material may, in similar manner, be applied to the dipole elements themselves at the time they are ready for attachment to the supporting sheet. Note that the adhesive material should not volatilize when in space. For this reason, a thermo-setting resin might be most suitable. Another method would utilize a thermoplastic resin as the supporting sheet material. The needles could be sown onto the sheet when warm and molten. Upon cooling the dipole needles will be found to adhere properly to the sheet.

The planar sheet 10 with metallic dipole elements secured thereon may be rolled up into a cylinder for insertion into a missile nose cone or the like as shown by FIGURE 3 of the drawing. The cylinder may then be folded, rolled or coiled. When the supporting sheet panel 10, as rolled up and carried in a nose cone, is ejected into space, it may be easily unfolded or unrolled to present a large area of captive metallic dipole elements within range of earthbound radio transmitting and receiving stations in order to facilitate the unrolling and erection of the reflective panel in space one or more longitudinal ribs 15 may be formed in the panel or secured to the panel. These ribs may be formed of material that is impervious to gas or atmosphere and may be sealed at one end as shown by 16 of FIGURE 3. If the panel is rolled into cylindrical form in the atmosphere a certain amount of the atmosphere will be trapped within the hollow rib 15, and when the rolled panel is ejected into space, the entrapped atmosphere in the rib 15 will have sufficient pressure relative to the near vacuum of space to expand the rib 15 and unroll the panel as will be obvious to those skilled in the art. It will not be necessary to seal both ends of the rib 15 since once the panel is erected it will retain its unfolded and erected state in space indefinitely. It should be pointed out that for the purposes of this invention, the sheet need not be completely flat. Unrolling is required only to present the greatest reflective surface area which is reasonably possible. Alternatively, a source of gas under pressure (not shown) may be connected to the erecting rib 15 at the time of ejection of the panel into space.

Yet another manner of facilitating the unfolding and erection of the passive reflective panel in space would be to enclose a longitudinal coil spring 20 such as shown by FIGURE 4 of the drawing within the longitudinal tube or rib 15. Alternatively, the longitudinal coil spring 20 may be secured to the panel 10 at individual points along its length instead of enclosing it within a tube or rib structure 15. Various modifications of such arrangements will be obvious to those skilled in the art.

If desired the supporting panel of flexible sheet material may be a fabric comprised of warp and woof yarns 30, 31 of electrically insulative material as shown by FIGURES 5 and 6 of the drawing. A plurality of randomly disposed metallic filaments such as shown for example at 32-34 may be secured to extend generally perpendicularly from one surface of the fabric panel (FIGURE 5) alternatively, the filaments such as shown by 35 and 36 of FIGURE 6 of the drawing may extend generally perpendicularly from opposite sides of the fabric panel respectively. Alternatively, the filaments may be randomly disposed within the plane of the fabric panel. It will be noted from the enlarged detail of both FIGURES 5 and 6 of the drawing that each of the respective metallic filaments 32-36 may be of different lengths randomly positioned relative to each other. That is to say, no particular pattern of varying lengths of one filament adjacent another filament is to be observed. The random orientations of the reflecting metallic dipole elements as used with any of the forms of the invention assures that the reflective characteristics of the antenna will be substantially omnidirectional and non-polarized over its entire bandwidth. The provision of the flexible support sheet or fabric of insulating material to which the metallic reflecting dipole elements are secured and fixed in randomly oriented positions and sizes assures that such aggregation of reflective needles will not be dispersed relative to each other in space. The panel can be made quite large in area and can be easily foldable to a small compact form for insertion in a missile nose cone. After the panel has been unfolded and erected in space it will retain its shape indefinitely since it will not be affected by punctures when micrometeorite particles or the like pass through the fabric or supporting sheet. The vast numbers of reflective metallic filaments that may be supported on a large area of flexible support sheet or fabric will assure that the efficiency and effectiveness of the reflective antenna will be maintained notwithstanding occasional punctures of the panel of supporting material by the micro-meteorite particles. In addition, since the exact shape of the supporting panel as unfolded in space is not critical to the functioning of the individually supported and randomly positioned and oriented dipole reflective elements, any changes in attitude or surface shape of the supporting panel during its orbiting period in space will not seriously reduce the efficiency and effectiveness of the antenna.

Although many variational embodiments of the invention will be apparent to those skilled in the art, a specific example of the invention might comprise a plastic film panel having an adhesive surface to which are bonded a plurality of aluminum filaments varying in diameter from a diameter of one thousandth to one ten thousandth of an inch and having a length of approximately 1.5 centimeters so as to be resonant to a microwave radio signal of about 1000 megacycles. Obviously the various different lengths for the metallic filaments may be greater than or less than 1.5 centimeters depending on the center frequency and the bandwidth of the electromagnetic radiations to be reflected.

I claim as my invention:

1. A passive reflective antenna to be orbited in space comprising, a panel of electrically insulative foldable sheet material adapted to be folded and stored within a space capsule under atmospheric air conditions and ejected from the capsule into space, at least one tubular rib of material impervious to atmosphere secured to and extending along said panel in a direction for erection of the panel in space, a plurality of metallic filaments supported in random positions from a surface of said material, each of said metallic filaments having a length corresponding to one half the wavelength of the desired frequency of electromagnetic radiation to be reflected to thus function as a reflective antenna for such radiation, and said tubular rib entrapping ambient air while said panel is folded under atmospheric air conditions whereby when a folded panel is

ejected from the capsule into the near vacuum of space the panel is unfolded to a variable extent to form an enlarged area of reflective antenna with no predetermined geometric configuration.

2. A passive reflective antenna to be orbited in space comprising, a panel of electrically insulative foldable sheet material adapted to be folded and stored within a space capsule under atmospheric air conditions and ejected from the capsule into space, at least one tubular rib of material impervious to atmosphere secured to and extending along said panel in a direction for erection of the panel in space, a plurality of metallic filaments of different lengths supported in random positions from a surface of said material, each of said metallic filaments having a length in a range of lengths from minimum to maximum corresponding to one half the wave length of the desired frequency band of electromagnetic radiations from minimum to maximum frequencies to be reflected to thus function as a

broad band reflective antenna for such radiation, and said tubular rib entrapping ambient air while said panel is folded under atmospheric air conditions whereby when a folded panel is ejected from the capsule into the near vacuum of space the panel is unfolded to a variable extent to form an enlarged area of reflective antenna with no predetermined geometric configuration.
